UNITED STATES PATENT OFFICE.

CHARLES E. AVERY, OF TRENTON, NEW JERSEY, ASSIGNOR TO MANHATTAN ELECTRICAL SUPPLY COMPANY, OF JERSEY CITY, NEW JERSEY, A CORPORATION OF NEW JERSEY.

ELECTRIC FAN.

1,188,384.

Specification of Letters Patent. Patented June 27, 1916.

Application filed June 6, 1914. Serial No. 843,364.

To all whom it may concern:

Be it known that I, CHARLES E. Avery, a citizen of the United States, residing in the city of Trenton, in the county of Mercer and State of New Jersey, have invented certain new and useful Improvements in Electric Fans, of which the following is a specification.

My present invention relates to an electric fan, and more particularly to that type of fan known as an oscillating fan, in which the motor frame is pivotally mounted upon a stationary base or standard and is so connected by intermediate mechanism with the shaft of the motor that it receives therefrom an oscillatory motion when the fan is in operation.

One object of the invention is to provide an intermediate or oscillating mechanism which can be attached to a standard fan, with slight if any changes in the parts thereof to convert it from a stationary into an oscillating fan, and which can without derangement be removed with the cap of the motor casing for the inspection or repair of the armature of the motor.

A further object is to provide, as a part of such mechanism, a new and improved differential gear, which, while securing the necessarily great reduction required to convert the rapid rotation of the motor-shaft into the slow oscillatory movement of the motor frame, combines simplicity and strength of construction with compactness of form.

Still another object is to provide such mechanism with an adjustable connection by means of which the degree of oscillation of the motor frame and consequently of the fan can be quickly and easily regulated, from a maximum to zero, where the motor frame will remain stationary, without stopping the motor.

With these and other objects in view, the invention comprises certain novel features of form, arrangement, and combination of parts hereinafter fully described, with reference to the accompanying drawings, which form a part of this specification and in which—

Figure 1 is a side elevation, partly in section, of a standard electric fan equipped with oscillating mechanism embodying the several features of my invention; Fig. 2, a section on the line 2-2 of Fig. 1, looking

upward in the direction indicated by the arrows; Fig. 3, an enlarged horizontal section on the line 3-3 of Fig. 1; Fig. 4, a similarly enlarged vertical section on the line 4-4 of Fig. 1, looking in the direction indicated by the arrows; and Fig. 5, a horizontal section on the line 5-5 of Fig. 4, looking downward in the direction indicated by the arrows.

The same reference characters indicate like parts throughout the several figures of the drawings.

Referring to the drawings, 1 indicates the base or standard of an electric fan which supports the usual motor frame or casing 2, provided with a detachable cap 2^a; and fan 3. In a standard non-oscillating fan the motor casing is mounted upon the standard, with a universal joint connection, by means of a short post 4 which at its lower end has a tongue 5 pivoted upon a transverse axis within the slotted upper end 6 of the standard, being adjustably secured in the desired angular position therein by a thumb screw 7, and at its upper end either carries fixed therein a vertical spindle bearing in a hub or sleeve on the lower side of the motor casing or is provided with a bearing for a spindle fixed in the hub of the motor casing, thus forming a vertical pivotal bearing about which the motor casing may turn and upon which it is held in the desired angular adjustment by a thumb screw; the tongued lower end of the post being preferably slotted centrally and the post and spindle bored out longitudinally to form a central longitudinal passage through which the wires for the electric circuit may be extended from within the hollow upright of the standard to the interior of the motor casing where they are secured to suitable binding posts. As here illustrated, however, an additional annular block or ring 8 is interposed between the pivoted post 4 and the motor casing, the hollow spindle 9 fixed in the upper end of the post 4 being extended so as to pass up through the block and into the bearing provided therefor in the hub or sleeve 10 on the lower side of the motor casing. The annular block is held in any desired angular position upon the post by a thumb screw 11 and the motor casing, while free to swing on its pivotal bearing upon the spindle, is secured thereon against accidental displacement by a set screw which extends

110

into an annular groove 12 formed around the upper end of the spindle.

Within the bearing hub 13 of the rear detachable cap 2^a of the motor casing is secured, by set screw 15 or otherwise, an elongated bearing bushing 14 which is provided in its lower side with an opening 16 to admit the wick of the usual oil cup 17 screwed into the lower side of the bearing hub. This bushing provides at its inner end a bearing for the rear end of the motor-shaft 18, while its rearwardly extended outer end supports an elbow casing, and the oscillating mechanism inclosed therein, which comprises a short horizontal arm 19 rigidly secured at its outer end to or cast upon the bushing and, somewhat offset therefrom, a longer downwardly extending vertical arm 20. The oscillating mechanism comprises a shaft 23 which, mounted within the horizontal arm of the upper casing, is journaled at one end in the outer end of the bushing 14, within which it is directly but detachably coupled to the motor-shaft by means of a tongue 24 fitting into a slot 25 provided therefor in the end of the motor-shaft, and at its outer end in a bearing 27 formed in a plug 28 set into the outer cylindrical end of the casing arm. This horizontal shaft 23 carries a spiral gear or worm 29 in mesh with a second spiral gear or worm 30 carried by the shaft 31 which is mounted to rotate in bearings 32 and 33 within the vertical arm of the casing and is supported upon a spherical step bearing provided for its lower end by a ball 34. The upper end of the vertical arm of the casing, internally threaded, is closed by a screw plug 35.

An internal gear 36 is mounted upon the lower end of the vertical arm of the casing, concentric with the axis of the vertical shaft 31, by means of a flanged sleeve 37 which fits thereon and is secured thereto by set screws or in any suitable manner. A second internal gear 38, of slightly greater diameter than the first and formed around a recessed chamber in a shell or cap 39, is mounted to rotate upon the fixed gear concentric therewith and with the axis of the vertical shaft by means of an annular plate 40 which is attached by screw bolts to the flanged rim of the cap and so completes an annular grooved bearing around the outer surfaces of the fixed gear. The ball 34, on which as stated the vertical shaft 31 is stepped, is set into and carried by the inner face of the cap 39. Within the inclosed chamber formed by these two internal gears and resting upon the inner face of the rotating cap are two spur gears 41 and 42 which are mounted to rotate together, being either made integral or otherwise connected, upon a bearing 43 provided therefore on the lower end of the vertical shaft, eccentric to its axis and by which they are

held and moved around in engagement with the internal gears; the small gear 41 with the fixed, and the larger gear 42 with the rotating, internal gear.

A circular plate 44 is attached to the lower or outer flat face of the cap in which the rotating internal gear is formed, here shown by the same screw bolts by which the annular plate is secured to the flanged rim of the cap. This circular plate is upset to form a radially disposed groove 45 in its inner face, and along the center of the flat bottom of this groove is cut a slot 46 which extends from near the outer end of the groove inwardly to a point slightly beyond the center of the plate. A bearing post 47, which carries a loosely fitting bushing 48, is adjustably mounted upon the plate and the revolving cap to which it is attached by being passed through the slot 46 in the plate and screwed tightly into a nut 49 located in the radial groove of the plate and adapted to slide back and forth therein. The upper flanged end of the bushing and the nut are thus drawn together and, gripping the plate on the sides of the slot, hold the bearing post fixed in position at any point in the length of the slot. And, finally, the plate and revolving cap are operatively connected with the standard of the fan by a link 50 which at its outer rear end is pivoted upon the bushing on the adjustable bearing post and at its other or front end is pivoted at 51 within a transverse slot 52 formed in one side of the annular block 8.

Constructed as herein illustrated and described the operation of the oscillating mechanism is as follows: When the fan is in operation, the rotation of the motor shaft causes the horizontal shaft 23 coupled thereto to rotate at the same speed, and, through the spiral gears 29 and 30, also causes the vertical shaft 31 to rotate, but at a speed reduced by one-half since the spiral gears are so proportioned that it requires two revolutions of the gear 29 to effect one revolution of the gear 30. As the shaft 31 rotates the eccentric bearing at its lower end upon which the spur gears 41 and 42 are rotatably mounted carries those gears around a circular path, once for every two revolutions of the motor shaft, in engagement, respectively, with the fixed and rotating internal gears. The small gear 41, which as manufactured commercially has forty-one teeth, is by reason of its engagement with the fixed internal gear, made with forty-three teeth, caused to rotate in the reverse direction to that in which the vertical shaft 31 rotates and at a speed reduced in the proportion which the difference between the number of teeth of these two gears bears to the number of teeth of the small gear; namely, two revolutions to every forty-one revolutions of the shaft 31; and the larger spur gear 42, rotat-

ing as it does with the small gear, causes the larger internal gear and cap to rotate, in a direction which is the reverse of that in which the spur gears are rotating and in the same direction as the vertical shaft, but at a speed further reduced to two revolutions for each forty-eight revolutions of the two spur gears, such reduction being the proportion which the difference between the number of teeth of the large spur gear and of the rotating internal gear bears to the total number of teeth of the former. The reduction in speed of rotation of the motor shaft, reduced one-half by the spiral gears, is thus further multiplied or compounded by what may be called the compound differential gears, so that the rotating internal gear and cap make one revolution upon the fixed internal gear for every two hundred and eighty-one

$$(2/41 - 2/48 = 140.5 \times 2 = 281)$$

revolutions of the motor shaft. And the rotation of this cap, since the inner end of the link 52 is held in fixed relation with respect to the standard and when its outer end is pivoted off center as shown, causes the entire elbow casing to move back and forth in the arc of a circle and so oscillates the motor casing back and forth upon its pivotal mounting, once for each revolution of the cap and each two hundred and eighty-one revolutions of the motor shaft.

It is evident that the reduction in speed effected by the differential gears may be greatly varied, as desired, both by changing the number of teeth of the spur gears relative to those of the internal gears and by changing the number of teeth, either with or without a change in the diameter, of all four gears. For example, with a fixed internal gear having one hundred teeth, a rotating internal gear with one hundred and one teeth, and spur gears with ninety-nine and one hundred teeth respectively, the speed will be reduced to about one ten thousandth; and with gears each having about five hundred teeth the reduction will be approximately to one two hundred and fifty thousandth. However, by reason of the great reduction effected by my new compound differential, the gears can, for the purpose for which they are here used, be made both small in diameter and with large teeth, thus securing compactness and strength of construction and reliability in operation.

Another advantage is that the oscillating mechanism with practically all its operative parts completely inclosed is rigidly secured or cast upon and supported by the special bearing bushing which fits into the rear bearing hub of the standard motor casing and is therein secured in the same manner as is the usual bushing provided therefor, and that

its only other connection with the fan, made through the annular block 8, requires for the insertion of this block between the motor casing and pivoted post 4 only a different or longer spindle for the latter. Thus, by detaching the outer rear end of the link 50 from the bearing post 47, the rear cap of the motor casing can be detached and removed with the oscillating mechanism, for the inspection or repair of the armature, without opening the casing of or otherwise interfering with the oscillating mechanism.

It is also evident that the bearing post can be loosened and moved in the slot and then reset in any desired position radially of the rotating cap; and thus, without stopping the fan, the length of the arc through which the elbow casing travels and consequently the degree of oscillation of the fan, which depend upon the distance from the center of the cap at which the bearing post is fixed and which becomes zero when the post is brought to the inner end of the slot and set at the center of the cap, may easily be regulated or the fan made stationary.

While I have explained the principle of my invention and have specifically illustrated and described that form of mechanism which I now consider to be the best mode in which to apply that principle in practice, it will of course be understood that the several features of the invention may be variously modified in their details, within the scope of the appended claims, without departing from the spirit or sacrificing the advantages thereof.

What I claim as new, and desire to secure by Letters Patent, is—

1. In an electric fan, the combination, with a non-oscillating fan comprising the usual standard and motor casing pivotally mounted thereon and carrying the motor shaft and motor, of a block detachably secured between the standard and motor casing in fixed position relative to the standard, a casing detachably secured to the rear of the motor casing in fixed alignment with the motor shaft, a member mounted upon the lower side of said casing to rotate upon an axis parallel to the pivotal axis of the motor casing, transmission and reducing mechanism mounted within said casing in operative connection with the rotatable member thereon and detachably coupled to the motor shaft within the rear hub of the motor casing, and a link detachably connecting an eccentric bearing post upon said rotatable member with a fixed bearing upon said block.

2. In an electric fan, the combination with a non-oscillating fan comprising the usual standard and motor casing pivotally mounted thereon and carrying a motor shaft and motor, of a block detachably secured between the standard and motor casing in

- fixed position relative to the standard, an elbow casing detachably secured to the rear end of the motor casing with its horizontal arm in fixed axial alignment with the motor shaft and its vertical arm extending downward substantially to the bottom of the motor casing, a member mounted upon and closing the lower end of the vertical arm of said casing to rotate upon an axis parallel to the pivotal axis of the motor casing, a shaft mounted within the horizontal arm of said casing detachably coupled to the motor shaft within the rear hub of the motor casing carrying a worm at its rear end, a shaft mounted within the vertical arm of said casing carrying at its upper end a worm gear meshing with the worm on the horizontal shaft and at its lower end operatively connected through reducing mechanism with said rotatable member, and a link detachably connecting an eccentric bearing post upon said rotatable member with a fixed bearing upon said block.
3. In an electric fan, the combination, with a standard and a motor casing pivotally mounted thereon and carrying the usual motor shaft and motor, of a bearing bushing the inner end of which is detachably secured to the rear bearing hub of the motor casing and provides a bearing for the rear end of the motor shaft, an oscillating mechanism which is mounted upon the outer end of the bearing bushing and is operatively coupled to the motor shaft by the insertion of the bearing bushing in place within the bearing hub, and detachable means operatively connecting the oscillating mechanism to the standard of the fan.
4. In an electric fan, the combination, with a standard and a motor casing pivotally mounted thereon and carrying the usual motor shaft and motor, of a bearing bushing the inner end of which is detachably inserted in the rear bearing hub of the motor casing and provides a bearing for the rear end of the motor shaft and an oscillating mechanism which comprises a casing mounted upon and supported on the rear outer end of said bearing bushing and extending downwardly substantially to the bottom of the motor casing, a member mounted upon the lower end of said casing to rotate on an axis parallel to the pivotal axis of the motor casing, transmission and reducing means mounted within said casing in operative connection with said rotatable member and detachably coupled to the rear end of the motor shaft by the insertion of the bearing bushing in position within the bearing hub of the motor casing, and detachable means adjustable radially upon said rotatable member operatively connecting said member with a member secured in fixed position relative to the standard of the fan.
5. An oscillating mechanism for an electric fan, comprising a casing which is adapted to be secured to the rear cap of the motor casing of a standard non-oscillating fan in fixed axial alignment with the motor shaft, a member mounted on the casing to rotate upon an axis parallel to the pivotal axis of and substantially opposite the pivotal bearing of the motor casing upon the standard of the fan, transmission and reducing mechanism mounted within the casing in operative connection with said rotatable member and adapted to be automatically coupled to the rear end of the motor shaft of the fan by the securing of the casing in position upon the motor casing, a member which is adapted to be inserted between the motor casing and the standard of the fan and secured in fixed position relative to the standard, and means operatively connecting said rotatable member with said last mentioned member.
6. An oscillating mechanism for an electric fan, comprising an elbow casing which is adapted to be detachably secured by its horizontal arm to the motor casing of a fan, transmission and reducing mechanism mounted within and inclosed by the casing, means whereby the transmission and reducing mechanism is automatically coupled to the rear end of the motor shaft within the rear hub of the motor casing, a member provided with a radial slot extending to its center rotatably mounted on the lower end of the vertical arm of the casing and operatively connected with the transmission and reducing mechanism, and a bearing post adjustably mounted within the radial slot in said rotatable member whereby the oscillating mechanism may be both operatively and inoperatively linked to the standard of the fan.
7. An oscillating mechanism for an electric fan, comprising an elbow casing with horizontal and vertical arms which is adapted to be detachably secured by its horizontal arm to the rear cap of the motor casing of a fan, a horizontal shaft mounted to rotate within the horizontal arm of the casing, means whereby the horizontal shaft is coupled to the rear end of the motor shaft when the casing is secured to the rear cap of the motor casing, a shaft mounted to rotate within the vertical arm of the casing and geared at its upper end to the rear end of the horizontal shaft, a member provided with a radial slot extending from its center outwardly toward its circumference mounted to rotate upon the lower end of the vertical arm of the casing and operatively connected through reducing gears with the vertical shaft therein, and a bearing post adjustably mounted within the radial slot of the rotatably mounted member whereby said member may be operatively and inoperatively connected with the standard of the fan.
8. An oscillating mechanism for an elec-

- tric fan, comprising an elbow casing with a horizontal arm which is adapted to be detachably secured to the rear cap of the motor casing of a fan in fixed axial alinement 5 with its motor shaft and a downwardly extending vertical arm, a shaft mounted to rotate within said horizontal arm and provided at its outer front end with a tongue which is adapted to enter a slot in the rear end of 10 the motor shaft to automatically couple the two shafts together when the casing is secured in position on the motor casing, a shaft mounted to rotate within said vertical arm and geared at its upper end to the rear 15 end of the horizontal shaft, a member rotatably mounted upon the lower end of said vertical arm coaxial with the shaft therein and operatively connected through reducing gears with its lower end, and means adapted 20 to detachably connect said rotatably mounted member in operative relation with the standard of the fan.
9. An oscillating mechanism for an electric fan, comprising a casing which is adapted 25 to be secured to the rear cap of the motor casing of a fan in fixed axial alinement with its motor shaft, a vertical shaft mounted within and extending down through an opening in the lower side of the casing and 30 adapted to be operatively coupled to the motor shaft when the casing is secured in position upon the motor casing, an internal gear mounted in fixed position upon the lower side of the casing concentric with the 35 vertical shaft, a second internal gear of larger diameter mounted to rotate upon the lower face of the relatively fixed internal gear and adapted to close the lower side of the chamber formed by the two gears, two 40 spur gears of different diameters mounted to rotate together upon an eccentric bearing on the vertical shaft in engagement the smaller with the relatively fixed and the larger with the rotatable internal gear, and 45 an eccentric bearing post mounted upon the lower face of the rotatable internal gear whereby it may be operatively linked with the standard of the fan.
10. An oscillating mechanism for an electric fan, comprising an elbow casing with horizontal and vertical arms which is adapted 50 to be secured by its horizontal arm to the rear cap of the motor casing in fixed axial alinement with the motor shaft, a shaft 55 mounted within said horizontal arm which is adapted to be automatically coupled to the rear end of the motor shaft when the casing is secured in position upon the motor casing, a shaft mounted to rotate within the 60 vertical arm of the casing and carrying at its upper end a gear meshing with a worm on the horizontal shaft, an internal gear mounted in fixed position at the lower end of the vertical arm concentric with the shaft therein, a larger internal gear closed on its lower side and mounted to rotate upon and immediately below the relatively fixed internal gear, two spur gears of different diameters mounted to rotate together upon an eccentric bearing on the lower end of the vertical shaft 65 in engagement the smaller with the relatively fixed and the larger with the rotatable internal gear, and an eccentric bearing post mounted upon the lower face of the rotatable internal gear whereby the oscillating 70 mechanism may be detachably linked to a fixed bearing upon the standard of the fan.
11. An oscillating mechanism for an electric fan, comprising as elements thereof a bearing bushing adapted to be inserted in the rear bearing hub of the motor casing of a fan to provide a bearing for the rear end 75 of its motor shaft, a casing fixed at one end to the outer end of the bearing bushing, a shaft mounted to rotate within the casing and adapted to be detachably coupled to the rear end of the motor shaft when the bearing bushing is secured in position within the bearing hub of the motor casing, an internal gear mounted in fixed position upon the casing concentric with the shaft therein, and a second internal gear mounted concentric with the first internal gear to rotate thereon and adapted to be operatively connected with the standard of the fan, and two 80 smaller spur gears mounted to rotate together upon an eccentric bearing upon said shaft in engagement one with the fixed and the other with the rotatable internal gears.
12. An oscillating mechanism for an electric fan, comprising as elements thereof a shaft adapted to be coupled to the motor shaft of a fan in axial alinement therewith, a second shaft mounted at right angles to said first shaft and operatively connected 85 therewith, two internal gears mounted concentric with said second shaft and with each other, one relatively fixed and the other to rotate and carrying an eccentric bearing post by which it may be operatively connected with the standard of the fan, and two smaller spur gears mounted to rotate together upon an eccentric bearing on said second shaft in engagement one with the relatively fixed and the other with the rotatable internal gear.
